Primary Examiner — Derrick Holland(74) *Attorney, Agent, or Firm* — McCarter & English, LLP; Keith Toms; Heath T. Misley(57) **CLAIM**

The ornamental design for an electrical connector, as shown and described.

DESCRIPTION

FIG. 1 is a front view of an electrical connector showing our new design;

FIG. 2 is an exploded front view thereof;

FIG. 3 is a perspective view of the electrical connector shown in FIG. 1; and,

FIG. 4 is an exploded perspective view thereof.

The broken line portions of the figure drawings are included to show unclaimed subject matter only and form no part of the claimed design.
